INFANT CORRECTIVE DEVICE

James B. Stewart, Knoxville, Tenn., assignor to
The Stewart Manufacturing Co., Knoxville,
Tenn., a corporation of Tennessee

Application February 16, 1932. Serial No. 593,331

4 Claims. (Cl. 128—133)

The present invention relates to improvements in infant corrective devices, and has for an object to provide an improved device so constructed as to be attachable to the arm of an infant to act as a restraint from bending the arm, whereby to bring the thumb into the mouth of the infant, thus breaking and avoiding the obnoxious and unsanitary habit of thumb-sucking.

10 While there have been some devices conceived for this purpose they have failed particularly in that they involve an objectionable amount of harness upon the infant, are difficult and harmful of application, and are costly in construction and apt to become bent or distorted, so as to make future application or the removal of the devices difficult, if not impossible.

It is another object of the invention to avoid the difficulties with the former devices and to 20 provide an inexpensive, light, yet durable device for free and easy application to the arm of the infant without pinching, cutting or bruising the soft flesh, but at the same time being well calculated to prevent the infant from getting 25 its thumb up into its mouth.

With the foregoing and other objects in view, the invention will be more fully described hereinafter, and will be more particularly pointed out in the claims appended hereto.

30 In the drawing, wherein like symbols refer to like or corresponding parts throughout the several views,

Figure 1 is a perspective view of an improved device constructed according to the present invention and indicated in a position of application to the infant's arm.

Figure 2 is a similar view detached from the arm and with the parts in open position ready for attachment or removal.

40 Figure 3 is a top plan view of the device in the closed position, and

Figure 4 is a similar view in the open position of the parts.

45 Referring more particularly to the drawing the device may consist of one or more strands of wire bent and fashioned to provide an arm loop 5 and a wrist loop 6 at opposite ends of the device. The wire is preferably round in cross section and is of a resilient character in order to avoid injury or cutting or scratching and to provide for a certain flexibility of movement in response to the flexure of the muscles of the infant's arm. These 50 rings or loops 5 and 6 are connected by side members preferably formed from twisted portions of the doubled wire. The inside member 7 is pref-

erably shorter than the exterior member 8 to agree with the natural distances between such portions of the forearm and elbow. The forward ring or loop 6 is constituted of two substantially semi-elliptical half sections which are divided at 60 both ends. At one side the divided loop sections join with the outside arm 8 by connecting strands 9 and 10, which strands as they emerge from the plane of the ring 6, extend for an appreciable distance in approximately straight and parallel 65 directions before they become intertwined in the twisted length 11 of the outer side member. Where these strands 9 and 10 are overturned at right angles into the plane of the ring 6 they form substantially radial parts 12 and 13 for a 70 short distance before branching out into the elliptical sections of the ring 6 and they are overlapped one upon another in order to reinforce the sections of the ring 6 and avoiding one section being bent out of the elliptical plane from the 75 other section.

At the opposite sides of the loop 6 there are formed longer strands 14 and 15 forming parts of the inner side member 7. Fashioned from one of these elongated strands 15 is a hook 16 adapted 80 to engage with the other strand 14. The two elliptical members are shown as having abutting shoulders 17 when the hook 16 is engaged with the elongated strand 14, for which see Figure 3. The hook 16 is so fashioned that it will prevent 85 any radial movement of the strands with respect to the ellipse and this confinement of the strand 14 by the hook 16 reinforces the action of the abutting shoulder 17 in holding the ring 6 in a 90 stable condition when interlocked about the wrist of the infant.

The elongated strands 14 and 15 merge with a twisted section 18 of the inner shorter side member 7.

The elbow ring 5, which is larger than the 95 wrist ring 6 is also of elliptical or round configuration and is carried by the side members.

The outer side strands 19 and 20 of the side arm 8 support the divided sections of the ring 5 at this side and these strands 19 and 20 form a 100 hinge joint at the point 21 which is remote from the plane of the ring 5 and which, therefore, allows the separation of the strands 19 and 20 and the opening of the ring 5 as the device is put in place or slid up on the arm. The inherent 105 resiliency of the wire will draw the sections of the ring 5 together lightly upon the arm. The strands 19 and 20 join with a twisted section 22 of the outer side member.

At the inner side of the elbow ring 5 the same 110

is also divided into half sections and elongated strands 23 and 24 of the inner side member 7 carry such inner ends of the sections of the ring 5. The strands 23 and 24 are twisted; however, 5 in wide loops which may move in and out upon one another sufficient to give the ring 5 a quality of expansibility. One of the strands carries a hump 25 and the other strand an outwardly offset portion 26 through which the hump is adapted 10 to engage and over which it slips, the inherent resiliency of the wire causing the snapping of the hump within the offset portion and thereby holding the ring 5 contracted, except when pressure is put upon the same to expand it.

15 The inner arm side member 7 is provided with one or more enlarged loops 27 and the outer side member includes one or more enlarged loops 28; such loops being for the purpose of receiving 20 pliers or other appropriate implement for rotating these flat loops and thereby imparting twist to the sections 18, 29, 11 and 22 of the side members. In this way the sections may be shortened or lengthened and also the twisted sections may be made to creep along further into the various 25 pairs of strands at the ends of the side members adjacent the rings 5 and 6. Consequently the opening capacity of the rings may be adjusted.

The ends of the wire forming the device may be brought together and tied in an appropriate 30 knot indicated at 30.

In the use of the device, it will be noted that the device employs only two rings 5 and 6 and that there are no ribbons or other tying or attaching 35 devices required to extend about the infant's arm in order to hold the device in place but the device is self sustaining and will remain in place without doing violence to the infant and without annoying the infant.

However, the device will avoid the bending of 40 the elbow so as to bring the thumb of the infant into proximity to its mouth.

The device is applied by first opening the hook or catch 16, as indicated in Figure 4, and separating 45 the elbow ring or loop 5 to the outer position, as also indicated in Figure 4. The loop 5 is then introduced over the hand and up along the arm until the opposite ring 6 has engaged over the hand and come to a position about the wrist; whereupon the ring 5 is released to contract of 50 its own resilient force and the hook 16 is engaged over the bar or strand 14 to restrict the ring 6 and prevent its casually slipping over the hand of the infant.

55

60

65

70

75

The inner and outer side members 7 and 8 are disposed upon the inner and outer sides of the arm so as to avoid the crooking of the arm so far as to enable the thumb to enter the mouth.

It is obvious that various changes and modifications may be made in the details of construction and design of the above specifically described embodiment of this invention without departing from the spirit thereof, such changes and modifications being restricted only by the scope of the following claims.

What is claimed is:—

1. An infant corrective device comprising substantially rigid side members, substantially parallel strands carried at the ends of said side members, half ring sections carried by said strands and being openable and closable through the strands, a hook formed upon one strand and adapted to interlock with the companion strand, a hump formed on another strand, an offset in the companion strand cooperating with said hump, and adjustable twisted sections in the side members for adjusting the lengths and the tension of said strands.

2. An infant corrective device comprising side 100 members formed of wire and including spaced twisted portions inwardly of the ends thereof, wide flat loops between said twisted portions for receiving a tool to adjust the twisted portions, strands extending outwardly of the twisted portions, and a resilient ring carried by said strands at each end of the side members.

3. An infant corrective device comprising substantially rigid side members, substantially parallel strands carried at the ends of said side members, half ring sections carried by said strands and being openable and closable through the strands, a hook formed upon one strand and adapted to interlock with the companion strand, a hump formed on another strand, and an offset 115 in the companion strand cooperating with said hump.

4. An infant corrective device comprising a substantially rigid side member, substantially parallel strands at each end of said side member, 120 half ring sections carried at each end of the side member on the ends of the strands, one section being openable and closable through the strands, a hook formed upon one strand and adapted to interlock with the companion strand.
